Attorney

UNITED STATES PATENT OFFICE

JOHN B. BLOSSER, OF COOKS, MICHIGAN

STEPLADDER

Application filed November 8, 1930. Serial No. 494,431.

The present invention relates to ladders, and more particularly step ladders which while capable of universal use are especially adapted to be used in the gathering of hand picked fruit such as cherries, peaches, and the like.

The object of the present invention is to provide a ladder of substantial construction yet not too heavy, capable of being adjusted to varying levels of ground; and in which vibration is reduced to a minimum, and especially so when the operator is on the top-most steps of the ladder. It is readily apparent that the elimination of vibration is of substantial importance, as many times women and children are employed to pick the fruit from a substantial height, necessitating in some instances ladders 6 to 12 feet in height. One of the causes of vibration will be understood from the following: A ladder may be well made, but if the bracing used to prevent the ladder from falling over is connected at the center of the very top of the ladder, when the operator shifts his weight to one end of the top step, the ladder will spring downwardly and forwardly. When the operator shifts to the other end of the step, vibration will result. When the ladder is in use, the operator constantly shifts his weight as he reaches in different directions to gather the fruit. One of the main objects of the present invention is to reduce the vibration to a minimum.

Another object of the present invention is the provision of a pocket for holding the ladder legs together while the ladder is being handled. Broadly stated, the invention comprises in a ladder, the combination of side rails, steps therebetween, a pair of rail end-members carried by the side rails, a brace member pivotally attached to the rail end-members to permit the brace member to swing outwardly and inwardly, and braces pivotally mounted for lateral movement on the brace member and adapted to be moved inwardly and outwardly with the brace member.

In the more specific form of the invention, the brace member is made in the form of a channel to snugly receive the braces and al-

low them to have a lateral movement through the channel. In making the brace member, it is preferred to form the same from sheet metal and shape and fold it to form a channel for the lateral movement of the braces therethrough. However, it is to be understood that this is merely the preferred material, and that many other materials may be utilized. All of the elements of the ladder may be made of wood, but in that case the ladder will not be as substantial and as free from vibration as if the brace member and the rail end-members are made of a metal, and preferably, as stated, of sheet metal which lends itself easily to manipulation. The brace pivots are preferably in the lower portion of the brace member. However, the position of the pivots may be somewhat varied and still come within the spirit of the invention. In the preferred form of the invention the braces are mounted on the brace pivots so that the upper portions thereof abut to form with said brace pivots a truss support. There is also provided a projecting member carried by the brace member and preferably located above the horizontal plane of the brace pivots, the projecting member acting as an additional support for one of the braces. The rail end-members are preferably in the form of a channel having substantially front and rear walls, a top wall and an end wall, the side rails being fastened to the rail members between the front and rear walls and adjacent to the end walls. However, this construction of the rail end-members may be varied and still come within the scope of the present invention.

The present invention also contemplates certain novel details of combination, construction and arrangement of parts of the improved ladder herein disclosed whereby certain important advantages are obtained, as will be more fully described hereinafter and pointed out in the claims, it being understood that the invention is susceptible of various changes in construction which may be made within the scope of the claims without departing from the spirit of the invention.

The present invention will be disclosed and

fully explained by reference to the accompany drawing, wherein:

Figure 1 is a perspective view;

Figure 2 is a horizontal section taken on line 2—2 of Figure 1;

Figure 3 is a vertical section taken on line 3—3 of Figure 2;

Figure 4 is a partial rear view showing the ladder braces held in place when the ladder is being handled.

The ladder consists of a frame comprising side stiles or rails 1, steps 2, and a top step 3. Braces 4 and 4A are provided. Fixed on to the ends of rails 1 are rail end-members 5, preferably in the form of channels or sleeves. The rail end-members have a front wall 8, a rear wall 9, an upper wall or flange 10, and an end wall 11, the latter abutting against the rail 1 as shown in Fig. 3. The rail end-members 5 may be made of any suitable material, but preferably of sheet metal. The rail end-members 5 are secured by means of bolts 6 and 7 to the rails 1, and the top step 3 of the ladder is fastened to the rail end-members 5 by means of rivets 12 and 13. The brace member 14 is adapted to have braces 4 and 4A pivotally mounted therein by means of bolts 15 and 16. The brace member or ladder head is preferably in the form of a channel having a rear wall 17, a front wall 18, and relatively short end walls 19. The lower portions of the rear and front walls 17 and 18 form lips 20 and 21 and it is preferred that the bolts 15 and 16 be mounted in the lower portion of the lips. The brace member 14 is pivotally mounted on the rail end-members by means of pivoting members, for example bolts 22. Fastened to the brace member above the horizontal plane of the brace pivots is a projecting member 23, for example a bolt, which acts as an additional support for the top portions of the braces 4 and 4A.

A pocket 24 is provided for holding the braces 4 and 4A when the ladder is not being used. The pocket comprises a shaped metal member having a rear wall 25 adapted to be fastened to the step 2 by means of screws or the like, and projecting flanges or clip members 27 and 28. When using the ladder, the brace 4 may be placed in the clip 27 and then the brace 4A is clamped in the flange or clip 28 by springing the brace therein. Both of the braces will spring out under the clips and be held in place. These clips 27 and 28 function best when they exert a small spring action on the braces.

It will be noted that when the braces 4 and 4A are standing on varying levels, the top portions thereof abut, as shown in Figure 2. The braces below the abutting point are pivotally mounted to the brace member 14 by means of pivots 15 and 16. When an operator stands upon one of the steps, for example the top step 3, his weight is supported by a

truss arrangement formed by the braces 4 and 4A being pivoted on the pivots 15 and 16 and abutting against each other, as shown in Figure 2. The truss effect obtained is enhanced by the effect of the legs resting on the ground. The projecting member 23 in the preferred form of the invention increases the truss effect. It will be noted that the ends 19 of the brace members 14 are fastened to the top rail end-members 5 to which is fastened top step 3 of the ladder. Therefore, any weight on the end of the ladder will not cause it to swing downwardly since it is held in place by the brace 14 and the lever action of the braces 4 and 4A. When the ladder is resting on level ground, the top portions of the braces 4 and 4A abut, forming a support. When the ladder rests on uneven ground, the projecting member 23, as shown in Figure 2, acts as a fulcrum for one of the braces, the lower end of the particular brace resting on the projection 23 being of course on the ground which acts as a substantial support. It is, therefore, clear that regardless of the particular position of the legs, that is whether they are placed on level ground or uneven ground, the ladder when in use has a truss lever action which reduces vibration to a minimum.

The construction of the end-members may be considerably varied. For example, the end wall 11 may be omitted, and this in some instances is the preferred construction.

What I claim is:

1. In a ladder, the combination of side rails, steps therebetween, a pair of rail end-members carried by the side rails, a brace member pivotally attached to said rail end-members to permit the brace member to swing outwardly and inwardly, braces pivotally mounted for lateral movement on said brace member and adapted to be moved inwardly and outwardly therewith, said braces projecting upwardly beyond their respective pivoting points, and a projecting member carried by said brace member above the horizontal plane of the brace pivots, and positioned to allow said braces to contact with one another and form with the projecting member a truss support.

2. In a ladder, the combination of side rails, steps therebetween, a pair of rail end-members carried by the side rails, a channel brace member pivotally attached to said rail end-members to permit the brace member to swing outwardly and inwardly, braces pivotally mounted for lateral movement in said channel brace member and adapted to be moved inwardly and outwardly therewith, said braces projecting upwardly beyond their respective pivoting points, and a projecting member carried on said brace member above the horizontal plane of the brace pivots, and positioned to allow said members

to contact with one another and form with the projecting member a truss support.

3. In a ladder, the combination of side rails, steps therebetween, a pair of rail end-members carried by the side rails, a brace member shaped to provide a channel for movement of the braces therebetween and having end walls closing the upper portion of the channel and pivotally attached to said rail end-members to permit the brace member to swing inwardly and outwardly, and braces pivotally mounted for lateral support in said channel brace member and adapted to be moved inwardly and outwardly with said brace member.

4. In a ladder, the combination of side rails, steps therebetween, a pair of rail end-members carried by the side rails, a brace member shaped to provide a channel for movement of the braces therebetween and having end walls closing the upper portion of the channel and pivotally attached to said rail end-members to permit the brace member to swing inwardly and outwardly, braces mounted for lateral movement in said channel brace member and adapted to be moved inwardly and outwardly with the brace member, and a projecting member carried by said brace member above the horizontal plane of the brace pivots, said projecting member acting as an additional support for one of said brace members.

5. In a ladder, the combination of side rails, steps therebetween, a pair of rail end-members carried by the side rails, a brace member having a top wall, substantially parallel front and back walls spaced from one another forming a channel just sufficient to snugly receive the braces, and end walls closing the upper portion of the channel and pivotally attached to said rail end-members to permit the brace member to swing inwardly and outwardly, and braces pivotally mounted for lateral movement in said channel brace member.

6. In a ladder, the combination of side rails, steps therebetween, a pair of rail end-members carried by the side rails, a brace member having a top wall, substantially parallel front and back walls spaced from one another forming a channel just sufficient to snugly receive the braces, end walls closing the upper portion of the channel and pivotally attached to said rail end-members to permit the brace member to swing inwardly and outwardly, braces pivotally mounted for lateral movement in said channel brace member, and a projecting member carried by said brace member above the horizontal plane of the brace pivots, said projecting member acting as an additional support for one of said brace members.

7. In a ladder, the combination of side rails, steps therebetween, a pair of rail end-members having substantially parallel front

and rear walls, a top wall and an end wall, said side rails being attached to the rail end-members between said front and rear walls and adjacent to the end walls, a channel brace member pivotally attached to said rail end-members to permit the brace member to swing inwardly and outwardly, braces pivotally mounted for lateral movement in the channel brace member allowing the braces to be adjustable for varying ground levels, and a projecting member carried by said brace member above the horizontal plane of the brace pivots, said projecting member acting as an additional support for one of said brace members.

8. In a ladder, the combination of side rails, steps therebetween, a pair of rail end-members having substantially parallel front and rear walls, a top wall and an end wall, said side rails being fastened to the rail members between said front and rear walls and adjacent to the end walls, a brace member having a top wall, substantially parallel front and back walls spaced from one another forming a channel just sufficient to snugly receive braces, and end walls closing the upper portion of the channel and pivotally attached to the side walls of the rail end-members to permit the brace member to swing inwardly and outwardly, and braces pivotally mounted for lateral movement in said channel brace member.

9. In a ladder, the combination of side rails, steps therebetween, a pair of rail end-members having substantially parallel front and rear walls, a top wall and an end wall, said side rails being fastened to the rail members between said front and rear walls and adjacent to the end walls, a brace member having a top wall, substantially parallel front and back walls spaced from one another forming a channel just sufficient to snugly receive braces, and end walls closing the upper portion of the channel and pivotally attached to the side walls of the rail end-members to permit the brace member to swing inwardly and outwardly, and braces pivotally mounted for lateral movement in said channel brace member.

10. In a ladder, the combination of side rails, steps therebetween, a pair of rail end-members carried by the side rails, a brace member pivotally attached to said rail end-members to permit the brace member to swing outwardly and inwardly, brace pivots attached to said brace member, and braces mounted on said pivots for lateral movement and having the upper portions thereof abutting to form with said pivots a truss support, said braces being adapted to be moved

inwardly and outwardly with said brace member.

11. In a ladder, the combination of side rails, steps therebetween, a pair of rail end-members carried by the side rails, a brace member pivotally attached to said rail end-members to permit the brace member to swing outwardly and inwardly, brace pivots attached to said brace member, braces mounted on said pivots for lateral movement and having the upper portions thereof abutting to form with said pivots a truss support, said braces being adapted to be moved inwardly and outwardly with said brace member, and
- 15 a projecting member carried by said brace member above the horizontal plane of the brace pivots, said projecting member acting as an additional support for one of said braces.
20. 12. In a ladder, the combination of side rails, steps therebetween, a pair of rail end-members carried by the side rails, a brace member made of sheet metal and shaped to form a channel pivotally attached to said rail end-members to permit the brace member to swing inwardly and outwardly, brace pivots attached to said brace member, and braces mounted on said pivots for lateral movement and having the upper portions
- 25 thereof abutting to form with said pivots a truss support, said braces being adapted to be moved inwardly and outwardly with the brace member.
30. 13. In a ladder, the combination of side rails, steps therebetween, a pair of rail end-members carried by the side rails, a brace member made of sheet metal and shaped to form a channel pivotally attached to said rail end-members to permit the brace member to swing inwardly and outwardly, brace pivots attached to said brace member, braces mounted on said pivots for lateral movement and having the upper portions thereof abutting to form with said pivots a truss support, said braces being adapted to be moved inwardly and outwardly with the brace member, and a projecting member carried by said brace member above the horizontal plane of the brace pivots, said projecting member acting
- 35 as an additional support for one of said braces.

In testimony whereof I hereunto affix my signature.

JOHN B. BLOSSER.
